UNITED STATES PATENT OFFICE.

LESLIE F. PORTER, OF PASSAIC, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed July 24, 1924. Serial No. 727,869.

This invention relates to telephone systems, and particularly to toll switching systems wherein an operator establishes and supervises connections between a calling subscriber and a called subscriber at a distant point.

The object of the invention is to provide an improved circuit arrangement to take care of toll calls to and from machine switching offices, it being particularly an object to render the operation more flexible through the use of certain common apparatus and to render the results more certain through the extension of the use of the supervisory signaling means.

A feature of this invention is a positional dialling arrangement wherein direct current is applied to one of the talking strands of the cord by the operation of a master dialling key to cause an alternating current relay to be bridged across the talking strands of a trunk leading to the distant end thereof, and wherein alternating current applied to the talking strands of the cord through a dial associated with the cord by the operation of the master dialling key is interrupted by the dial to cause the bridged alternating current relay to translate the operation of the dial into impulses of any character required to set switches associated with the distant end of the trunk.

Another feature of the invention is a positional or master ringing arrangement whereby ringing on a connected trunk is controlled by direct current over one of the talking strands of the cord circuits in use.

Another feature is a positional or master transfer arrangement for switching calls from one position to another on a toll switchboard, wherein selective operation of signaling devices at the positions is attained by varying the resistance in series with a battery supplied to one of the talking strands of the cord without making use of the sleeve or the other talking strand, the selective operation of the signaling devices being attained through the use of marginal relays directly connected to such strands of the trunk with which the cord is associated.

A further feature of the invention is a

sleeve supervisory arrangement wherein the bridged supervisory equipment is associated with the trunk instead of the cord and the signals are transferred by this equipment to the sleeve of the cord, this equipment being controlled from the distant end of the trunk. An operator's talking key individual to the cord will, when operated, transfer the sleeve circuit of the cord directly from a supervisory signal to a marginal relay arrangement which controls the supervisory signal so that the supervisory signal will be properly controlled in either normal or operated position of the key.

The invention is shown in three figures which, when placed end to end in the order in which they are numbered, will disclose means for completing a connection from a calling subscriber to a called subscriber at a distant point. Fig. 1 discloses a toll switching trunk; Fig. 2, an operator's position; and Fig. 3, a toll line leading to a distant point.

It is believed that the invention will be more fully understood from the following detailed description of the operation of the circuits. Let it be assumed that the subscriber at station 100 wishes to establish a connection with another subscriber at a distant point.

Following out the usual practice the subscriber at station 100 establishes a connection to a recording toll operator who makes a record of the station calling and the station to be called whereupon the calling subscriber hangs up and awaits developments. The information taken by the recording operator is passed to a line operator whose equipment is illustrated in Fig. 2. This operator thereupon inserts plug 200 of one of her cord circuits into jack 101 which forms a terminal of a train of automatic switches through which the subscriber at station 100 may be reached. A circuit is established from battery through signal 201, contact springs 203 and 204 of key 202, sleeve of plug 200, sleeve of jack 101, winding of relay 102 to ground. Relay 102 becomes energized in this circuit without result at the present time. The operator then actuates

80

85

90

95

100

the right hand portion of key 202 and the left hand portion of key 211. The operation of key 202 results in the establishment of a circuit from ground, contact springs 205 and 206 of key 202, winding of relay 207 to battery and ground resulting in the energization of relay 207. The actuation of the right hand portion of key 202 also results in the establishment of a substitute circuit for the energization of relay 102. This circuit extends from grounded battery through the windings of relays 209, 210, contact springs 208 and 204 of key 202 and thence over the circuit previously traced through the winding of relay 102. The actuation of the right hand portion of relay 202 further opens the circuit of signal 201 so that this signal now becomes deenergized. Relay 209 is energized at this time, but relay 210 being marginal does not operate. The energization of relay 209 results in the energization of relay 212 which is at this time without effect.

The actuation of the left-hand portion of dialing key 211 results in the establishment of a circuit from grounded battery, resistance 216, contacts 217 and 218 of key 211, contacts 219 and 220 of key 221, upper outer armature and front contact of relay 207, tip conductor of plug 200, tip of the jack 101, repeating coil winding 103, armature 104 and its back contact of relay 105, winding of relay 106 to ground. Through the energization of relay 106, a circuit is established from the tip of jack 101 through repeating coil winding 103, condenser 107, winding of alternating current relay 108, inner lower armature and front contact of relay 106, repeating coil winding 109, to the ring of jack 101 and thence to the ring of plug 200, front contact and lower outer armature of relay 207, contact springs 222 and 223 of key 221, contact springs 224 and 225 of key 211, to a source of alternating current, the other connection to this source of A. C. being extended through the impulse springs 226 of dial 228, condenser 227 to a point in the circuit leading to repeating coil winding 103 so that alternating current relay 108 is now in a circuit with the source of alternating current and it becomes energized. The energization of relay 108 results in the establishment of a circuit from ground, armature and contact of relay 108, resistance coils 110, winding of relay 111 to battery and ground. Relay 111 becomes energized and bridges relay 112 across the trunk leading to the train of automatic switches indicated at the right of relay 106. Such an arrangement of switches may be that shown, for example, in Patent 1,474,008 to Stokely. The connection is now in a stable condition awaiting further action on the part of the operator.

The operator now manipulates the dial 228 to send a series of any given number of

impulses. Such impulses are in the form of short interruptions of the alternating current circuit for the energization of relay 108 and upon each such interruption relay 108 causes the circuit of relay 111 to be opened, 70 which in turn opens the circuit of relay 112 and in this manner momentarily removes the bridge from across the trunk and thus operates the selectors leading to station 100.

If the operator has sent a suitable number of impulses, the trunk will be extended to the line of substation 100. If this line is found to be idle and is seized by the last switch in the series, the current traveling through relay 112 will be reversed in the 80 manner fully explained in the Stokely Patent 1,474,008 hereinbefore mentioned.

Relay 112 is a polarized relay and will respond to this reversal of current, whereupon a circuit is established from ground, 85 armature and front contact of relay 112, winding of relay 105 to battery and ground. Relay 105 becomes energized and locks in a circuit including its own winding, front contact and armature 113, armature and front contact of relay 102 to ground. The energization of relay 105 results in the opening of the circuit for the energization of relay 106 and this relay now becomes deenergized and removes the bridge containing relay 112 90 from across the trunk leading to the substation 100. The deenergization of relay 106 also results in the opening of the circuit of alternating current relay 108 so that this relay now becomes deenergized causing in turn the deenergization of relay 111. The battery connection extending through armature 104 is now transferred through the corresponding front contact of relay 105 to the winding of relay 114 which relay, however, 100 being marginal does not become energized while resistance 216 is in series therewith. The trunk conductors leading to station 100 are now extended through the back contacts of relays 106 and 114 and a circuit is established through repeating coil winding 115, 105 winding of relay 116, front contact and armature 117 of relay 105, repeating coil winding 118 to the other side of the trunk so that relay 116 is now bridged across the 110 trunk and is energized by the current flowing therein. The energization of relay 116 places a resistance 119 in parallel with the winding of relay 102 and so reduces the resistance of the circuit between the sleeve of jack 101 and ground that the marginal relay 210 becomes energized. Upon the energization of this relay a circuit is established from ground through resistance 215, armature and front contact of relay 210, contact 125 springs 214 and 213, signal 201 to battery and ground so that this signal becomes effective to notify the operator that the line of substation 100 has been seized.

The operator now restores the dialing key 130

211 to normal and having established a connection to substation 100 proceeds, without signaling such station, to establish a connection to the wanted line. For this purpose she inserts the plug 233 in the outgoing jack 300, whereupon a circuit is established from battery through the winding of relay 235, winding of relay 236, contact springs 237 and 238 of the right hand portion of key 202, sleeve of plug 233, sleeve of jack 300, normal contacts of the outer left hand armature of relay 301, winding of relay 302 to ground. Relay 302 becomes energized in this circuit and causes the energization of relay 303 whereupon a circuit is established from battery through the alternate contacts of the right hand armature of relay 303 and thence in parallel through the busy signals 304, 305 and 306 to ground so that these busy signals, each associated with a jack connected to the toll line, are energized to indicate that this toll line is busy.

The current flowing in the circuit including the windings of relays 235, 236 and 302, besides being sufficient to energize relay 302 as hereinbefore described, causes the energization of relay 235, but relay 236 being marginal does not become energized at this time. Relay 235 closes a circuit for the energization of relay 240, which is without effect at the present time. The connection is now in a stable condition awaiting further action on the part of the operator.

The operator now manipulates the ringing key 229 so as to actuate the right-hand set of contact springs. This results in the establishment of a circuit from battery, through the contacts 241 and 242 of key 229, contacts 243 and 244 of key 211, contacts 245 and 246 of key 221, inner upper armature and front contact of relay 207, tip of the plug 233, tip of jack 300, upper winding of impedance coil 318, winding of marginal relay 307, resistance 308, to ground. Current in this circuit is sufficient to energize marginal relay 307 since no resistance similar to resistance 216 is included in the circuit. Relay 307 in attracting its armatures, connects a source of ringing current to the windings of repeating coil 309, whence by induction ringing current is transmitted to the distant end of the toll line and the operator at that point is summoned. The operator now restores her ringing key, and when the operator at the distant end of the toll line answers, information regarding the wanted line is passed and such wanted subscriber is connected to the toll line in the usual way.

Let us first assume that the wanted subscriber's line is connected to the toll line immediately by the distant toll operator and that this operator has notified the originating operator whose equipment is shown in Fig. 2, that she is ringing. The originating operator thereupon actuates the left-hand

portion of key 229 to summon the subscriber at station 100. Upon the actuation of this key, a circuit is established from battery, through contacts 230 and 231 of key 229, contacts 232 and 218 of key 211, and thence over a circuit previously traced through the winding of marginal relay 114. Marginal relay 114 becomes energized in this circuit and connects a source of ringing current 119 to the connection leading towards substation 100. This causes the signal at station 100 to be actuated, and the subscriber at that point will remove his receiver from the switchhook.

It should be noted that with key 229 in normal position, the operator's telephone set is connected to the toll line in the following manner: Tracing the circuit from the tip of plug 233, the connection extends through the front contact and inner upper armature of relay 207, contacts 246 and 245 of key 221, contacts 244 and 243 of key 211, contacts 242 and 257 of key 229, contacts 249 and 258 of key 229, armature and front contact of relay 240, windings 259 and 260 of the induction coil forming part of the operator's telephone set, condenser 261, contacts 262 and 255 of key 229, contacts 254 and 253 of key 211, contacts 252 and 251 of key 221, inner lower armature and front contact of relay 207, to the ring of plug 233. It will be noted that the operator's telephone receiver 263 is connected across the winding 260 through the back contacts and inner armatures of relay 264, and that the operator's telephone transmitter 265 is connected in a circuit which is inductively coupled with the windings 259 and 260.

In a similar manner, with key 229 in its normal position, the operator's telephone set is connected to the tip and ring conductors leading through plug 200. Connection may be traced from the ring of plug 200, front contact and outer lower armature of relay 207, contact springs 222 and 223 of relay 221, contact springs 224 and 269 of key 211, contact springs 270 and 271 of key 229, condenser 261, transformer coils 260 and 259, through the front contact and armature of relay 212, contact springs 266 and 267 of key 229, contact springs 268 and 231 of key 229, contact springs 232 and 218 of key 211, contact springs 219 and 220 of key 221, outer upper armature and front contact of relay 207 to the tip of plug 200.

It will thus be noted that relay 212 controls the connection of the operator's telephone set to that end of the cord circuit terminating in plug 200, and that relay 240 controls the connection of the operator's telephone set to that portion of the cord circuit terminating in plug 233.

If the operator wishes to converse with the subscriber at station 100 to the exclusion of the distant subscriber she will actuate the

right hand contacts of splitting key 221 so that the connection between her telephone set and plug 233 is broken but the connection with plug 200 is undisturbed. When 5 she actuates the left hand contacts of key 221 the opposite effect is obtained.

The last operation described was the manipulation of the left-hand portion of key 229, resulting in the operation of relay 114 10 and the ringing of substation 100. Key 229 is then restored to its normal position, and response of the subscriber at substation 100 is awaited. When the subscriber at this station answers, the trunk extending between 15 the repeating coil windings 115 and 118 and substation 100 is rendered "dry" in the manner fully described in the Stokely Patent 1,474,008 hereinbefore mentioned. Relay 116 is thereupon deprived of current and it re- 20 stores its armature to normal whereupon the connection through resistance 119 to ground is now traceable through resistance 120 and the front contact and armature 121 of relay 105 to battery. This connection results in a 25 decrease of current flow through marginal relay 210, so that such relay restores its armature to normal and causes the signal 201 to become deenergized. This shows the operator that the subscriber at station 100 has 30 answered and she may now leave the connection by restoring key 202 to normal, whereupon the conversation between the parties to the connection will take place.

At the termination of this conversation 35 when the subscriber at station 100 replaces his receiver on the switchhook, relay 116 will become energized and set up the condition heretofore described resulting in the energization of marginal relay 210, so that signal 40 201 will be energized.

The signal 234 associated with plug 233 is arranged in a similar manner to the signal 201 associated with plug 200, but since the 45 relay 236 has not become energized during this connection as hereinbefore described, the signal 234 does not become energized. No switchhook supervision over the toll line is provided (in the present disclosure) so that the operator has to rely on signal 201 for 50 notification of the end of a conversation. It will be noted, however, that when the key 202 is in normal position, as when the operator has the plug 233 in jack 300 and is 55 busy tending to some other connection, then the supervisory signal 234 is in circuit with the sleeve conductor and relay 302 and will be actuated in the manner to be hereinafter described should the distant operator ring and thus operate relay 310. She may then 60 take the plug 201 out of jack 101 and plug 233 out of jack 300, and the connection will be restored to normal. The removal of plug 200 from jack 101 causes the deenergization of relay 102 and consequently the deenergization 65 of relay 105, so that the bridge across

the trunk leading to substation 100 is removed and the train of switches allowed to return to normal. The removal of plug 233 from jack 300 allows the deenergization 70 of relay 302 and the consequent deenergization of relay 303. Shortly thereafter, busy signals 304 to 306 will be deenergized, and the toll line apparatus will be placed in its normal condition.

In case the distant toll operator signals 75 the outward toll operator, before the connection has been taken down and while key 202 is in its normal position, ringing current applied at the distant end of the toll line will operate relay 310 in an obvious circuit. 80 Relay 310, in operating, releases relay 312, which relay is normally operated. Relay 312, in releasing, connects ground at its contacts to operate relay 301 in the following circuit: battery, winding of relay 301, left-hand alternate contacts of relay 303 and to ground at contacts of relay 312. Relay 301, in operating, completes a circuit for relay 330 which relay operates in series with interrupter 331, thereby alternately attracting 85 and releasing its armature. In practice, interrupter 331 operates relay 330 about 120 times per minute. Relay 301, when operated, transfers the holding circuit for relay 302, previously completed over the sleeve of 90 the jack and plug to battery 280 through lamp 234, to battery in series with resistance 332 over the outer left alternate contacts of relay 301. It should be noted that relay 302 is of such resistance that it does not permit 100 sufficient current to flow through the filament of lamp 234 to cause its illumination, when these two devices are in series. Relay 301, in operating, also completes a substitute 105 low resistance circuit for lamp 234 which can be traced from ground, through the winding of relay 334, right-hand normal contacts of relay 330, inner left alternate contacts of relay 301, inner left normal contacts of relay 315, outer left normal contacts of relay 314, 110 to the sleeve of the jack and thence through lamp 234 to battery and ground. Due to the low resistance of relay 334, lamp 234 now lights. Relay 334, also operates in this circuit and supplies a substitute holding ground 115 for relay 301 in place of the ground supplied by relay 312, which ground will be removed as soon as the ringing current ceases and relay 310 restores. When relay 330 operates in step with interrupter 331 it opens the previously described low resistance circuit for lamp 234, including relay 334, and substitutes a higher resistance path to ground 120 which includes resistance 333 in which path lamp 234 does not receive sufficient current to keep it lighted. The operation of relay 330 which opens the energizing circuit of relay 334, completed through lamp 234, immediately provides an obvious substitute holding circuit for relay 334, including resistance 125 130

335. Under the foregoing conditions, as relay 330 operates in step with the interrupter, lamp 234 will be alternately connected in series with low resistance relay 334 and with 5 the higher resistance unit 333, thereby causing it to flash as an indication to the operator that she is being signalled by the distant office.

When the operator manipulates key 202 to 10 the right or talking position, lamp 234 and battery 280 are disconnected from the sleeve circuit of the cord and a high resistance circuit to battery including relays 236 and 235, is substituted therefor. When relay 330 releases on an open segment of interrupter 331, 15 relay 334, which is now in series with relays 236 and 235, releases due to the fact that it receives insufficient current in this circuit to hold it operated.

20 The release of relay 334 releases 301 which relay in turn opens the circuit of relay 330.

We will now assume that the operator at 25 the distant end of the toll line of Fig. 3 is unable to establish a connection to the wanted party immediately and she therefore advises the operator of Fig. 2 of this condition, whereupon the operator of Fig. 2 will remove the plug 233 from jack 300, allowing the toll line apparatus to restore to normal.

30 If it appears to the operator that the connection may not be secured within a reasonable time, she will also remove the plug 200 from the jack 101. Any later attempt to complete the call will be made in the usual

35 manner hereinbefore described. Assuming now that the distant toll operator desires a connection with station 100, she will ring on the toll line in the usual manner. Alternating ringing current coming in over the toll

40 line will be inductively transmitted through the repeating coil 309, through the armatures and back contacts of relay 307, the windings of relay 310 and condenser 311. Relay 310 momentarily attracts its armature

45 and opens an obvious circuit for relay 312, whereupon this relay momentarily causes the establishment of a circuit from ground, the normal contacts of relay 312, the left-hand armature and back contact of relay 303, the

50 left-hand winding of relay 313, to battery. Relay 313 attracts its armature and locks in a circuit from ground, its right-hand winding, its front contact and right-hand armature, the normal contacts and the right-hand

55 armature of relay 303, to battery and ground. At this time, relay 313 locks up under control of relay 303 and immediately places a busy condition on the toll line through a circuit established from battery, the left hand

60 armature and front contact of relay 313, through the windings of busy signals 304 to 306 in parallel, to ground. Through the right-hand armature of relay 313, a circuit is established from battery, the normal contacts and right-hand armature of relay 303,

the right-hand armature and front contact of relay 313, the right-hand armature and back contact of relay 314, the right-hand inner armature and back contact of relay 315 and signal 316, to ground. Signal 316 is associated with jack 317 which is placed before an inward operator. The cord circuits used by this inward operator, are the same as those furnished at outward positions so that we will now assume that the operator having 70 access to jack 317 will insert plug 233 into jack 317 to answer the call incoming over the toll line. Upon the insertion of plug 233 into jack 317 and the actuation of the right-hand set of contacts of key 202, a circuit will 75 be established from battery in series through the windings of relays 235 and 236, contacts 237 and 238 of key 202, sleeve of plug 233, sleeve of jack 317, back contact and outer left-hand armature of relay 314, back contact and inner left-hand armature of relay 315, normal contacts and the outer left-hand armature of relay 301, winding of relay 302, to ground. Relays 302 and 235 become energized in this circuit, but the marginal relay 90 236 does not respond.

Due to the energization of relay 235, relay 240 will become energized and the operator's telephone set will be connected to that end of the cord circuit leading through plug 95 233. Due to the energization of relay 302, relay 303 will now become energized and open the circuit for the energization of signal 316 so that this signal now is restored to normal. A substitute circuit for the energization of busy signals 304 to 306 is,

100 however, established through the alternate contacts of the right-hand armature of relay 303. Relay 313 now being deprived of current through its locking winding, restores to normal. The inward operator now has her telephone set connected to the toll line and may converse with the operator at the distant end and establish the connection

105 with station 100 over the trunk of Fig. 1 in the same manner as heretofore described. If an incoming call, as before described requires the attention of an outward or ticket writing operator, that is, the operator who has access to jack 300, then the inward operator upon receiving this information will manipulate her transfer key 272 to the right. A connection will thereupon be established from grounded battery, contact

110 springs 273 and 274, contact springs 262 and 255 of key 229, contact springs 254 and 253 of key 211, contact springs 252 and 251 of key 221, inner lower armature and front contact of relay 207, ring of the plug 233, ring of jack 317, lower winding of impedance coil 318, left hand winding of relay 315, left-hand winding of relay 314, to ground. Relay 315 is a normal relay but

115 relay 314 is marginal. However, since the connection described is from a source of 120

125 125 battery, the connection will be maintained. The connection will be maintained until the inward operator manipulates her transfer key 272 to the right. A connection will thereupon be established from grounded battery, contact

130 130 springs 273 and 274, contact springs 262 and 255 of key 229, contact springs 254 and 253 of key 211, contact springs 252 and 251 of key 221, inner lower armature and front contact of relay 207, ring of the plug 233, ring of jack 317, lower winding of impedance coil 318, left hand winding of relay 315, left-hand winding of relay 314, to ground. Relay 315 is a normal relay but relay 314 is marginal. However, since the connection described is from a source of 130

battery without a resistance 275 therein, both these relays will become energized. Upon the attraction of its armatures, relay 315 establishes a circuit from ground, the 5 front contact and outer left-hand armature of relay 315, the left-hand winding of relay 313, to battery and ground. At the same time, relay 315 opens at its back contact and inner left-hand armature the hereinbefore 10 described circuit for relay 302, and this relay in releasing opens the circuit of relay 303 so that now a circuit for the energization of the locking winding of relay 313 is completed as hereinbefore described. This 15 circuit also extends battery current through the right-hand armature and front contact of relay 314, the right-hand winding of relay 314, signal 319, to ground. Signal 319 is associated with the jack 300 before the 20 outward operator. The operation of relays 314 and 315 opens the sleeve circuit through jack 317, and causes the deenergization of relay 235 and the relay 240, so that the operator is disconnected from the cord circuit 25 terminating in plug 233. She therefore restores key 202 to normal and takes the plug 233 out of jack 317. This leaves the connection in the following condition: The relays 302 and 303 are in normal condition 30 and relays 313 and 314 are both locked under control of the normal contacts of the right-hand armatures of relay 303. Through the energization of relays 313 and 314, signal 319 is actuated and will remain 35 in this condition until the outward operator responds, and the busy signals 304 to 306 are operated under control of relay 313.

It may be well to explain at this time that if the incoming call required the services of a through operator instead of an outward or ticket writing operator, the inward operator would actuate the key 272 to the left. The through operator's cord equipment is the same as at the inward and outward position and so the inward operator by operating the key 272 to the left will cause the energization of signal 320, which is associated with the jack 321, before a through operator. In this case, it will be noted that 45 resistance 275 is included in the circuit through the left-hand windings of relays 315 and 314, and hence relay 314 being marginal, does not become energized at this time. Therefore, when relay 313 becomes 50 energized, a circuit will be established from battery through the normal contacts and the right-hand armature of relay 303, the right-hand armature and front contact of relay 313, the right-hand armature and back contact of relay 314, the inner right-hand armature and front contact of relay 315, through the right-hand winding of relay 315, signal 320, to ground.

When plug 233 is inserted into either jack 55 300 or 321, relay 302 will be reenergized as

hereinbefore described. This results in the energization of relay 303 and the opening of the locking circuit of relays 313 and 314 or 315, with the consequent deenergization of signal 319 or 320 as the case may be.

It should be noted that if after a connection is established, the key 202 is actuated to the left then the coil 276 is bridged across the cord and an obvious connection for the energization of relay 284 is established. Since in this manner relay 207 is not energized, then the operator has her set connected to both the plugs 200 and 233 and may monitor on the connection.

What is claimed is:

1. In a telephone system, an operator's position, cord circuits thereat, a trunk circuit accessible to said cord circuits terminating in an automatic switch, an alternating current relay individual to said trunk circuit for controlling said switch, an operator's dial common to said cord circuits for controlling said alternating current relay, a dialing key common to said cord circuits, a relay individual to said trunk, said relay being responsive to said key and having means to operatively connect said alternating current relay to said trunk.

2. In a telephone system, an operator's position, cord circuits thereat, a trunk circuit accessible to said cord circuits terminating in an automatic switch, an alternating current relay individual to said trunk circuit for controlling said switch, means responsive to direct current connected over a single conductor of a cord circuit and a corresponding conductor of said trunk circuit for bridging said alternating current relay across the talking conductors of said trunk circuit, a source of alternating current for energizing said alternating current relay, and a dial for interrupting the flow of alternating current through said relay.

3. In a telephone system, an operator's position, cord circuits thereat, a trunk circuit accessible to said cord circuits terminating in an automatic switch, an alternating current relay individual to said trunk circuit for controlling said switch, means responsive to direct current for rendering said alternating current relay operative, a source of alternating current for energizing said alternating current relay, an operator's dial, a dialing key at said position for associating said dial with a particular one of said cord circuits, said dialing key when operated completing a direct current path over a single conductor of a cord circuit and a corresponding single conductor of said trunk circuit to operate said means, and an alternating current path including said source of current, said dial, the talking conductors of said cord circuit, the talking conductors of said trunk and said alternating current relay.

4. In a telephone system, an operator's po-

sition, cord circuits thereat, trunk circuits accessible to said cord circuits, a marginal relay individual to each of said trunk circuits connected to a talking conductor of its associated trunk, a key at each of said positions common to the cord circuits thereat, means individual to each of said cord circuits for splitting the talking circuit thereof, a source of tone, said key operating to complete a circuit for said trunk marginal relay at one end of a cord circuit and operating to connect said source of tone to the other end of said cord circuit when said key is operated in one way, and to establish corresponding connections in the opposite direction when said key is operated in another way.

5. In a telephone system, an operator's position, cord circuits thereat, trunk circuits accessible to said cord circuits, a marginal and a non-marginal relay individual to said trunk circuit, a master ringing key common to said cord circuits at said operator's position, a master dialing key common to said cord circuits at said operator's position, a key individual to each said cord circuit for connecting said common key thereto, said keys operating to establish direct current paths to said relays over said cord circuit, said dialing key including a resistance in such path whereby said relays are selectively operated by said keys.

6. In a telephone system, an operator's position, cord circuits thereat, each of said cord circuits having a sleeve conductor, a supervisory signal, a trunk circuit accessible to said cord circuits, said trunk circuit having a pair of talking conductors and a sleeve conductor, supervisory means for controlling said sleeve circuit comprising a direct current relay bridged across the talking conductors of said trunk leading to the distant end thereof and a relay controlled over the said sleeve conductor, an operator's listening key individual to each cord circuit, said key when operated acting to transfer the cord sleeve circuit from said supervisory signal to a pair of relays, one of said relays being responsive to the control exercised by said supervisory means and acting through said key to control said supervisory signal whereby said supervisory signal is under control of said supervisory means in either normal or operated position of said listening key.

7. In a telephone system, an operator's position, cord circuits thereat each having a sleeve conductor, a supervisory signal in each sleeve conductor, a telephone line accessible to said cord circuits, said line having a pair of talking conductors and a sleeve conductor, an alternating current relay in bridge of said talking conductors at said position and responsive to ringing current incoming over said line, and means controlled

by said alternating current relay for intermittently operating said supervisory signal in a circuit including the sleeve conductor of said telephone line.

8. In a telephone system, an operator's position, a cord circuit thereat, a sleeve conductor associated with said cord circuit, a supervisory signal in said cord sleeve conductor, a ring-down toll line terminating at said position and accessible to said cord circuit, said toll line comprising a pair of talking conductors and a sleeve conductor, an alternating current relay at said position connected in bridge to said talking conductors of said line and responsive to ringing current incoming thereover, and means controlled by said alternating current relay and included in said sleeve conductor of said toll line for intermittently increasing and decreasing the resistance of said supervisory signal circuit.

9. In a telephone system, an operator's position including a cord circuit having a sleeve conductor, a telephone line terminating at said position including a pair of talking conductors and a sleeve conductor, a supervisory signal in said cord sleeve conductor and energized over said line sleeve conductor when said cord is connected to said line, an alternating current relay connected in bridge of said line talking conductors and operated in response to ringing current incoming over said line, and means associated with said line initially controlled by the actuation of said alternating current relay to alternately increase and decrease the current in said supervisory signal energizing circuit.

10. In a telephone system, an operator's position including a cord circuit having a sleeve conductor, a telephone line terminating at said position including a pair of talking conductors and a sleeve conductor, a supervisory signal in said cord sleeve conductor and energized over said line sleeve conductor when said cord is connected with said line, and means associated with said line responsive to ringing current incoming thereover for flashing said supervisory signal.

11. In a telephone system, an operator's position, a cord circuit thereat, a plurality of telephone lines terminating at said position and accessible to said cord circuit, a supervisory signal for said cord circuit energized when said cord is connected with one of said lines, and means responsive to ringing current incoming thereover when said cord circuit is connected with one of said lines for flashing said supervisory signal.

12. In a telephone system, an operator's position, cord circuits thereat, trunk circuits accessible to said cord circuits, a relay individual to each of said trunk circuits connected to a talking conductor of its associated trunk, a marginal relay individual to each

of said trunk circuits connected to said talking conductor, a plurality of keys at said position common to said cord circuits, one of said keys having means for establishing a circuit for energizing either of said relays, another of said keys having means for establishing a circuit for energizing only said

first relay, and means under control of said marginal relay for connecting alternating current to said trunk.

10

In witness whereof, I hereunto subscribe my name this 22nd day of July, A. D. 1924.

LESLIE F. PORTER.
